UNITED STATES PATENT OFFICE.

DANIEL EVERETT LOMBARD, OF FALL RIVER, MASSACHUSETTS.

WRENCH.

SPECIFICATION forming part of Letters Patent No. 762,483, dated June 14, 1904.

Application filed September 12, 1903. Serial No. 172,986. (No model.)

To all whom it may concern:

Be it known that I, DANIEL EVERETT LOMBARD, a citizen of the United States, residing at Fall River, in the county of Bristol and State of Massachusetts, have invented a new and useful Wrench, of which the following is a specification.

This invention relates generally to wrenches, and more particularly to that class thereof known as "sliding-jaw nut-wrenches;" and the object of the invention is to provide an improved construction whereby the adjustment of the sliding jaw can be quickly and easily accomplished and when once adjusted will be securely held against backward movement.

With these objects in view the invention consists in the novel features of construction, combination, and arrangement of parts, all of which will be fully described hereinafter and pointed out in the claims.

In the drawings forming part of this specification, Figure 1 is a perspective view of a wrench constructed in accordance with my invention. Fig. 2 is a longitudinal sectional view of the same. Fig. 3 is a transverse sectional view on the line 3-3 of Fig. 2. Fig. 4 is a view showing the fixed jaw and shank in elevation and the movable jaw and sleeve in section. Fig. 5 is a detail perspective view 30 of the sliding jaw and sleeve. Fig. 6 is a detail perspective view of one of the locking-plates carried by the sleeve. Fig. 7 is a detail perspective view of the lever-rods employed for disengaging the locking-plates 35 from the shank.

In constructing a wrench in accordance with my invention I provide a fixed jaw A, which is rigidly connected to the shank B, said shank terminating in a handle portion 40 B'. Sliding upon the shank B is the fixed jaw C and integral sleeve D. The shank B is constructed with parallel grooves B² in the opposite sides, and the face of the shank upon opposite sides of these grooves is serrated or 45 provided with ratchet-teeth B³, and it will be noted by reference to Fig. 4 that the teeth upon opposite sides of one of the grooves alternate with the teeth upon the opposite sides of the other groove, the purpose of which

will appear hereinafter. Openings D' are produced in the opposite sides of the sleeve D, and locking-plates E are arranged in said openings, there being two plates in each opening, each plate being grooved longitudinally, as shown at E', and upon opposite sides of the 55 groove the inner face of the plate is serrated or provided with ratchet-teeth E². These plates E are held in the openings D' by means of springs F, rigidly connected at one end to the sleeve D. The ratchet-faced plates are adapted to engage the ratchet-teeth upon the sides of the shank, thereby locking the sliding jaw upon the shank, and inasmuch as the teeth B³ upon the opposite sides of the upper and lower grooves B² are arranged alternately it is 60 obvious that a very fine adjustment can be had. The teeth are so constructed that the jaw C can be pushed along the shank toward the fixed jaw A; but the engagement of the ratchet-teeth will prevent any backward movement of the jaw. 65 For the purpose of disengaging the ratchet-plates I employ the lever-rods G, there being one rod for each plate, said rods resting in the grooves B² and turned upwardly at their forward ends, as shown at G', said upwardly or 70 outwardly turned end resting in the longitudinal groove E', as most clearly shown in Fig. 3. Each lever-rod is bent, as shown at G², providing a fulcrum upon which the lever is adapted to turn, the outer or rear ends of each pair of 75 lever-rods being connected by means of a cross-bar H, having a recessed boss H', in which the thumb and finger can fit for the purpose of easily manipulating the wrench. 80 The grooves E' are in alinement with the 85 grooves B², and ample space is thereby provided for the slight movement of the lever-rods necessary to disengage the ratchet-plates from the ratchet-teeth of the shank. The springs normally hold the plates in engagement with the shank, and for the purpose of disengaging said plates, so that the sliding jaw can be adjusted rearwardly or opened, it is only necessary to press the cross-bars H inwardly toward the shank, and the levers, 90 rocking upon the portions G², will press the plates E outwardly, and the jaw can then be adjusted to the proper position, and the mo-

ment pressure is removed from the levers the springs will throw the plates back into engagement with the shank.

Having thus fully described my invention, 5 what I claim as new, and desire to secure by Letters Patent, is—

1. A wrench comprising a fixed jaw and shank, a sliding jaw and sleeve, said sleeve having openings in the sides, spring-actuated 10 serrated plates arranged in said openings, and the levers adapted to throw the said plates outwardly, as set forth.

2. A wrench comprising a fixed jaw and shank, said shank being grooved longitudinally upon the sides and provided with ratchet-teeth upon opposite sides of each groove, a 15 sliding jaw and sleeve, the sleeve having openings in the sides, spring-actuated serrated plates arranged in said openings, and the levers adapted to slide in the grooves in the 20

shank, and press the serrated plates outwardly, for the purpose set forth.

3. A wrench comprising a fixed jaw and shank, said shank being grooved longitudinally upon the sides and provided with ratchet-teeth upon opposite sides of each groove, the 25 fixed jaw and sleeve, said sleeve having openings in the sides, plates arranged in said openings, each plate being grooved longitudinally and provided with ratchet-teeth upon its inner face, springs for holding the plates in the openings in the sleeve, levers adapted to slide in the grooves, each pair of levers being connected at their rear ends, all of said parts being arranged and adapted to operate substantially as described.

DANIEL EVERETT LOMBARD.
